UNITED STATES PATENT OFFICE.

CLARENCE D. BARNHART, OF BROOKLYN, NEW YORK, ASSIGNOR TO W. S. ROCKWELL COMPANY, OF NEW YORK, N. Y., A CORPORATION OF NEW JERSEY.

CONVEYER FOR FURNACES.

1,333,371.

Specification of Letters Patent. Patented Mar. 9, 1920.

Application filed September 16, 1919. Serial No. 324,247.

To all whom it may concern:

Be it known that I, CLARENCE D. BARNHART, a citizen of the United States, residing at 386 Crown street, Brooklyn, county 5 of Kings, and State of New York, have invented certain new and useful Improvements in Conveyers for Furnaces, fully described and represented in the following specification and the accompanying drawings, forming a part of the same.

This invention relates to a continuous automatic furnace in which the material or stock to be treated is placed in pans which are pivoted upon cross-bars connecting two 15 chains, which chains carry the pans automatically through the furnace at any predetermined speed, and discharge them automatically at the end of the required treatment.

20 Where the articles require hardening they are discharged into a tank of water, oil or other quenching liquid and their treatment is thus effected in a single continuous operation.

25 Where bright finished goods like brass articles are treated it is very desirable to protect them from the atmosphere until they are cooled, and such articles also may be discharged into a water-tank or similar 30 means of quenching to cool them before any exposure to the atmosphere.

The invention embodies a variety of additions and improvements which in such furnaces, facilitate the heating and cooling 35 of the stock and render the apparatus completely automatic.

The construction will be understood by reference to the annexed drawing, in which Figure 1 is a side elevation of a furnace provided with the improvements, the brick-work being broken away at the left-hand end of the furnace to show the arrangement of the conveyer and outlet-opening. Fig. 2 is a cross section through the outlet-chute 45 taken on line 2—2 in Fig. 1; Fig. 3 is a section taken on the same line, with a modification of the stock-delivering devices; Fig. 4 is a plan of the same in horizontal section on line 4—4 in Fig. 5, at the top of the channels which inclose the chain; Fig. 5 is a cross section on line 5—5 in Fig. 4; Fig. 6 is a longitudinal section taken at the center line 6—6 in Fig. 4; and Fig. 7 is a longitudinal vertical section of the pre-heater chamber attached to the inlet of the furnace-chamber.

A furnace-chamber *a* is shown with longitudinal grooves *b* in the side-walls *a'* of the chamber, and endless conveyer-chains *c* are fitted to move in the grooves and extend between driving-wheels *d* at their opposite ends.

Cross-bars *e* are connected to the chains, and pans *f* are pivoted or hinged upon the cross-bars so as to be carried therewith through the heating-chamber.

These pans are held horizontally in their movement through the chamber *a* by support upon the floor *p* of the chamber, or by track-rails *o* bedded in the floor and projecting upward to contact with the bottoms of the pans.

The floor is disposed below the level of the grooves in the side-walls, so that the pans pivoted upon the cross-bars *e* may move some distance above the floor of the 75 furnace-chamber, and thus permit a thorough circulation of the heated gases beneath the pans; the track rails sustaining the pans in such position above the floor of the chamber.

To discharge the stock automatically from the chamber, an outlet *g* is formed in the floor of the chamber near the discharge-passage *a'*, and means is provided to hold the pans level or in a horizontal position 85 during their travel through the heating chamber until they reach the outlet, where the rails *o* terminate, and permit the pans to swing down and discharge their contents into the outlet and through a chute *h* sloped 90 laterally through the side-wall of the furnace, at a suitable level to discharge directly into a car or box *i*, as shown in Fig. 2. The chute may have a self-closing cover *h'* hinged over its mouth, as shown in Fig. 2. 95

A quenching tank may obviously be placed beneath the chute to receive the stock and chill it before exposure to the atmosphere.

Fig. 3 shows the chute having its nozzle *h'* extended below the water level *k'* in a 100 tank *j*, thus operating to cool the goods without exposure.

An inclined conveyer *k* is shown to remove the goods from the water and deliver them into the car or receptacle *i*.

105 Burners *r* for fluid fuel are shown extended through the wall of the furnace to heat the chamber *a*, and it is obvious that the location of the conveyer-chains *c* in the grooves at the side-walls of the chamber re- 110

moves the chains from the hottest zone and thus promotes their endurance.

To protect the chains still further from the heat, a metallic channel shown at *l* in Figs. 4, 5 and 6 is inserted in the groove and arranged to wholly inclose the chain, excepting a longitudinal slot *l'* through which the cross-bars *e* project.

These so-called channels are made of metal, in longitudinal sections of any convenient length and built into the side-walls of the furnace when it is erected.

To economize in the fuel and to gradually heat the pans and stock as they enter the furnace-chamber, I provide a pre-heater *t* which is attached to the inlet *n* of the heating-chamber, through which the stock moves before it enters the chamber *a*.

To properly support the chains and to hold the pans horizontal, I extend the floor of the heating-chamber, and the channels in the side-walls, throughout the whole length of the pre-heater.

A vent-pipe *q* is shown extended from the pre-heater near its outer end, with a damper *q'* to regulate the escape of gases therefrom; and the provision of such a vent generates a current of the heated gases from the chamber *a* throughout the pre-heater, and thus enables it to produce the pre-heating effect which is desired.

The gases must escape from some vent, and the provision of the pre-heater utilizes the waste heat of such gases in pre-heating the stock.

The conveyer-chains extend outside of the pre-heater a sufficient distance to afford an opportunity (with a slow movement of the pans) to charge them with the required stock, and it will be observed that no further attention is required, as the chains are timed to produce the required exposure of the stock to the heat; when the stock is automatically discharged into a receptacle, which, if a car, may carry the goods to any desired point without any manual labor in loading the same.

I have not made herein any broad claim to extending a cooling pipe along the path of a conveyer-chain where propelled through a heated chamber, as I have made such claim in another application co-pending herewith.

Having thus set forth the nature of the invention what is claimed herein is:

55 1. In a continuous automatic furnace having an outlet in the floor near one end, the combination, with conveyer-chains movable along the opposite sides of the chamber, of cross-bars connecting the chains, and pans 60 hinged upon the cross-bars and held horizontal by support upon the floor of the furnace excepting at the outlet.

2. In a continuous automatic furnace, the combination, with the side-walls of the furnace-chamber having grooves therein near

the floor of the chamber and an outlet in the floor of the chamber near one end, of conveyer-chains movable in the grooves, cross-bars connecting the chains, and pans hinged upon the cross-bars and supported in a horizontal position through the chamber to the outlet.

3. In a continuous automatic furnace, the combination, with the side-walls of the furnace-chamber having grooves therein near the floor of the chamber, of conveyer-chains movable in the grooves, cross-bars connecting the chains above the floor of the chamber, pans hinged upon the cross-bars, and one or more track-rails projected upwardly from the floor of the chamber toward the cross-bars and holding the pans horizontal in their movement through the chamber.

4. In a continuous automatic furnace, the combination, with the side-walls of the furnace-chamber having grooves therein near the floor of the chamber and an outlet in the floor of the chamber near one end, of conveyer-chains movable in the grooves, cross-bars connecting the chains, pans hinged upon the cross-bars, and track-rails projected upwardly from the floor of the chamber excepting at the outlet, whereby the pans are held horizontal in their movement through the chamber and dropped into the outlet to discharge their contents thereto.

5. In a continuous automatic furnace, the combination, with the side-walls of the furnace-chamber having grooves therein near the floor of the chamber, of metallic channels fitted to the grooves with a slot upon the inner side of each channel, conveyer-chains movable in the channels, cross-bars extended through the slots and connected to the chains, and pans hinged upon the cross-bars whereby the chains are in great measure protected from direct contact with the heated atmosphere in the furnace-chamber.

6. A continuous automatic furnace constructed as in claim 4 and having the mouth of the outlet sloped toward the discharge-end of the furnace to restore the pans gradually to a horizontal position as they leave the furnace-chamber.

7. A continuous automatic furnace constructed as in claim 1 and having a pre-heater casing projected outwardly from the inlet of the furnace-chamber, and the conveyer-chains extended through the pre-heater, whereby the pans and their contents are pre-heated before their entrance into the furnace-chamber.

8. In a continuous automatic furnace, the combination, with the side-walls of the furnace-chamber having grooves therein near the floor of the chamber, of conveyer-chains movable in the grooves, cross-bars connecting the chains, and pans hinged upon the cross-bars and held horizontal by support

upon the floor of the chamber, and a pre-heater casing extended outward from the inlet of the furnace with the floor of the furnace and the side-grooves extended through such pre-heater, whereby the chains are protected from excessive heat both in the pre-heater and in the furnace-chamber.

9. A continuous automatic furnace constructed as in claim 1 and having a sloping chute extended from the outlet in the floor laterally through the side-wall of the fur-

nace at a suitable level to discharge directly into a receptacle.

10. A continuous automatic furnace constructed as in claim 1 and having a chute 15 extended from the outlet through the side-wall of the furnace with a normally closed cover hinging upon its outer end.

In testimony whereof I have hereunto set my hand.

CLARENCE D. BARNHART.
